BANDING MACHINE

Harold R. Schutz, Ottawa Hills, Ohio, assignor,
by mesne assignments, to Libbey Glass Com-
pany, Toledo, Ohio, a corporation of Ohio

Application April 27, 1935, Serial No. 18,571
Renewed October 29, 1936

27 Claims.

(Cl. 91—12)

This invention is directed to new and useful improvements in banding machines of the type used for applying colored paint or enamel bands to glassware, particularly drinking tumblers, for decorative purposes.

The machine comprises a turret on which are mounted a plurality of chucks for holding the articles to be banded, a plurality of paint reservoirs and series of paint applying discs positioned around the turret and means for moving the chucks from one series of discs to the next series for applying different colored bands to the articles on the chucks in predetermined design.

15 The primary object of this invention is to provide such a machine that may be efficiently operated by a minimum of operators to produce completely finished banded glassware at high speed.

20 Another object is to provide a machine that is to a great extent automatic in operation and will decorate glassware accurately with a plurality of different colored bands arranged in predetermined relationship.

25 A further object is to provide such a machine adapted to handle a plurality of glassware units at once and arranged compactly so as to take up the minimum of floor space.

Still another object is to provide a banding machine that will automatically hold the glass units on the chucks while they are being treated and will automatically release them from the chuck when they are finished.

Still a further object is to provide a banding machine in which the articles on the chucks are rotated by the paint applying discs when paint is being applied and by independent means at greater speed at other times whereby the paint is evenly distributed and running of the paint is averted.

35 By way of further explanation it is to be noted that when the tumbler leaves the paint applying discs it tends to bring with it from each disc a surplus of paint or enamel. This is known as the tail of the paint and the increased speed of rotation of the tumbler when it leaves the discs whips the tail of the paint into proper alignment with the applied band and distributes it evenly as stated.

40 Another object of this invention is to provide such a banding machine in which the painted articles are thoroughly dried before being automatically released from the chucks.

45 Still a further object is to provide means for retaining the decorated units loosely on the

chucks after being released from operable relation with the chucks and until removed to the lehr.

Another object is to provide such a machine with positive means for accurately positioning the chuck at the paint applying stations.

Still other objects and advantages will become apparent from an examination of the following detailed description.

In the drawings:

10

Fig. 1 is a side elevation partly in section of a banding machine embodying the improvements and inventions herein set forth.

Fig. 2 is a central vertical section view of a portion of the upper half of the machine shown in Fig. 1.

Fig. 3 is a plan view of the machine.

Fig. 4 is an enlarged section taken along the line 4—4 in Fig. 1.

Fig. 5 is an enlarged detailed section of the valve mechanism shown in Fig. 2, taken on line 5—5 of Fig. 2.

Fig. 6 is an enlarged section taken on line 6—6 of Fig. 2, showing the positioning mechanism.

The main elements of the banding machine are 25 a base A which supports the mechanism, a motor B for causing continuous movement of certain parts, a centrally and vertically positioned hollow rotatable shaft C operably geared to the motor B, two paint applying stations D comprising paint reservoirs and paint applying discs, a turret E carrying four chucks, a drier F and a take-off guard rail G.

In detail the shaft 1 of the motor B is keyed to a horizontally extending worm gear 2 appropriately mounted for rotation in anti-friction bearings 3 and 4 as clearly shown in Fig. 4. Worm gear 2 is meshed with a circular gear 5 that is also mounted in anti-friction bearings and is keyed to the hollow rotatable shaft C. A 40 housing 6 encloses these gears.

Just above this housing a vacuum supply pipe 7 leads to the shaft C which is provided with openings 8 at this point leading to its interior. Part of housing 6 extends upwardly past these openings and around the shaft and is provided with a chamber 9 communicating with the openings 8. A threaded opening 9a is provided into which the supply pipe 7 is threaded, thus providing a continuous communication between the supply pipe 7 and the interior of the shaft C. The joint thus formed by the shaft and the extended portion of the housing is sealed against leakage to the atmosphere by means of threaded

gland 10 and packing material 10a clamped therein.

Higher on shaft C is keyed a bevel gear 11 that is meshed with another bevel gear 12 that 5 is in turn keyed to a horizontal shaft 13 which extends through the housing 14 of the lower portion of the machine and which has mounted on its outer end a pulley wheel 15.

The shaft C is reduced in diameter at its 10 upper end. A portion of the shaft at this point is provided with threads 16. A circular friction plate 17, with a split hub 18 having threads 19 to cooperate with the threads 16, is adjustably mounted on the shaft by means of the threads 15 and a screw 20 positioned through the split part of the hub which is unloosened to permit vertical adjustment and is tightened to clamp the hub to the shaft.

Above the friction plate 17 at its upper end 20 the shaft has two openings 21 communicating with its interior. A sleeve 22 is non-rotatably mounted around the shaft, has a chamber 22a communicating with openings 21, is provided with sealing members 23 and 23a and is supported by arm 24. Four outlets 25 lead from the sleeve and into these are threaded four supply pipes 26. A plug 27 closes the upper end of the shaft.

The top surface 28 of the housing 14 is a cam 30 plate provided with an annular adjustable cam 29 and a stop plate 30 having a stop member 30a with stop grooves 30b at predetermined positions for the purposes hereinafter stated. A set screw 29a holds the cam 29 in the position 35 desired. A bushing 31 surrounds the shaft C, is positioned between the cam plate and the shaft, is provided with a shoulder 32 immediately above the cam plate and extends upwardly therefrom.

40 The turret E is rotatably mounted around said bushing 31 above the shoulder 32 and on the anti-friction bearings 33. The turret comprises four forked arms 34 which extend upwardly and outwardly and in each of which is pivotally mounted a chuck mechanism 35 comprising a housing 36, a hollow rotatable shaft 37, a drive wheel 38 on the inner end of the shaft and a chuck assembly 39 on the outer end. The mechanism is pivotably and adjustably mounted 45 between the arms of the forked member 34 by means of a U-shaped bracket 40 secured to the under part of housing 36 that is provided with three conical holes 41 at each side. Conically pointed bolts 42 extend through the arms of member 34 and bear in the holes 41 dependent 50 upon the height adjustment desired. Mounted on the top of housing 36 is an arm 43 provided with a knob 44. The chuck assembly 39 comprises a tapered wooden head 45 provided with longitudinally extending ribs 45a, mounted on the end of shaft 37 and movable longitudinally thereon, a head 46 on the end of the shaft and a helical spring 47 positioned around the shaft to force cylinder 45 against head 46. A stop 55 and sealing member 48 is provided with an annular groove 48a to contact the rim of the article to be banded. A port 49 opens to the inside of shaft 37 and is positioned so as to be closed by cylinder 45 when in normal position. Adjacent the drive wheel 38 at the other end of shaft 70 37 are ports 50 surrounded by an extension 51 of housing 36 which is provided with a chamber 52 communicating with the ports. The end of the extension 51 is closed by a gland 53 which 75 seals the connection with the rotatable shaft. A

pipe 54 is threaded in the extension 51 and communicates with chamber 52. An apertured lug 55 is secured to the underside of extension 51 at the inner end. One end of coiled spring 56 is secured to lug 55 and the other to an anchor- 5 age 57 on the lower portion of the turret E so as to normally hold drive wheel 38 in contact with the upper surface of friction plate 17. A glass tumbler 58 is shown on the chuck.

For each such chuck assembly there is a valve 10 59 mounted on the lower portion of the turret and comprising an inlet port 60, and outlet port 61, and an exhaust port 62. A valve seat 63 and plate 64 are provided for opening and closing the connection between the inlet and outlet ports and a valve seat 65 and plate 66 are provided for opening and closing the exhaust port 62. These plates are loosely mounted on valve stem 67 between nut 68 and shoulder 69 on the outer end of the stem. A coil spring 70 20 positioned around the stem between the plates forces them away from each other. Above nut 68 another coil spring 71 is positioned around the stem and normally keeps the plate 66 on its seat 65 to close the exhaust port and the plate 25 64 in open position to connect the inlet and outlet ports. Secured to the lower end of the stem 67 and extending from the valve housing 72 is a cam follower 73. When follower 73 is forced upwardly by engagement with cam 29 30 valve plate 66 is unseated and valve plate 64 is seated to close the connection between the inlet and outlet ports and open the exhaust port to the atmosphere. Threaded in the housing 12 and communicating with the inlet port is 35 a pipe 74 and similarly a pipe 75 communicates with the outlet port. Pipe 74 communicates through proper pipe and hose connections with its supply pipe 26 and pipe 75 with pipe 54 that leads to the inside of hollow shaft 37 on the 40 chuck mechanism.

Depending from the turret below each forked member 34 is a housing 76 within which is a downwardly extending vertically movable follower 77 provided with a reduced portion 78 45 around which is positioned a coil spring 79 and a threaded head 80 which receives a nut 81 above a shoulder 82 in the housing. The lower end of the follower 77 is undercut as at 83 and bevelled as at 84. A threaded hole 85 is provided in the side of the housing, a vertical groove 86 is in the side of the follower and a bolt 87 threaded through hole 85 and projecting into groove 86 prevents the follower from turning out of position. The spring 79 holds the follower in extended position.

Each paint applying station is mounted on an outwardly extending bracket 88 and comprises a rotatable shaft 89 extending radially from the machine mounted on supports 90 and having 60 mounted on its inner end a pulley wheel 91 above the pulley wheel 15. These are operably joined by a belt 92. Removably mounted on shaft 89 between the supports 90 are a plurality of vertically resilient steel paint applying discs 93 65 adapted to rotate with the shaft. The discs are vertically resilient by means of floating hubs yieldably held in position with springs and may be arranged in various positions relative to each other and to the discs at the other station.

Below the paint applying discs at each station is a paint reservoir 94 into which the discs extend. Oscillatable fins 95 are positioned in the reservoirs to agitate the paint or enamel. Arms 96 secured to the fins are all joined together by 70 75

means of a bar 97, the inner end of which is pivotally joined to the lower end of lever 98, the outer end of which is slidably mounted through bracket 99.

- 5 A cylinder 100 is mounted on shaft 89 near its inner end and is provided on its outer surface with an eccentric groove 101. Lever 98 is pivotally mounted at its center to a bracket 102 and the inner side of its upper end has a stud 103 that 10 extends into and follows groove 101 when shaft 89 is rotated.

Positioned beneath the path of the chucks for an arc of 160° after leaving the second paint applying station is a hot air manifold 104 which 15 directs heated dry air upon the rotating freshly banded tumblers. The air is forced through the manifold by a blower 105 and the air is warmed by a heater 105a of any desired type positioned between the blower and the manifold.

- 20 From a point adjacent the end of the drier manifold 104 is mounted a vertical arcuate take-off guard rail 106 positioned in the same horizontal plane as the chucks and outward from the ends of the chucks a short distance and extending 25 for about 60° adjacent the path of the chucks. This rail is mounted on bracket 107 and is horizontally adjustable by means of bolts 107a and slot 107b depending upon the height of the glassware banded.

- 30 The supply pipe 1 communicates with the vacuum pump 108 of any desired type to present suction to certain parts of the machine.

In operation the motor B through the gearing hereinabove described causes the friction plate 17 35 and the disc bearing shaft 89 to continuously rotate. In normal position the friction plate contacts drive wheels 38, causing the chucks to also rotate. It is clear that the paint applying discs pick up paint from the reservoirs and that the 40 fins keep the paint stirred. Paint of one color is within one reservoir and of another color in the other one.

Vacuum is present up to the port 49 on the chuck for the reason that the valve 59 is in normal or open position and closed to the atmosphere.

The operator takes a glass tumbler to be banded and pushes it on a chuck until its rim contacts the stop member 45. This moves the 50 wooden head 45 inwardly against the spring 47 and thereby opens port 49 in the outer end of shaft 37. Air is thus exhausted from the tumbler so as to hold the tumbler in applied position. The operator then grasps the knob 44 of arm 43 55 and swings the chuck in a counterclockwise direction to a point just past the first paint applying station and then swings it back, in a clockwise direction, until the end of follower 77 abuts the stop shoulder 30b which positions the tumbler exactly above the first series of paint applying discs. The operator then moves the chuck downward until the tumbler contacts the edges of the paint applying discs 93. In this movement it is to be noted that drive wheel 38 60 is moved out of contact with the friction plate 17 and the chuck ceases to rotate. The contact between the paint applying discs and the side of the glass tumbler rotates the chuck while the paint is applied. When the first series of bands 65 have been applied the operator lifts the tumbler from the discs, moves the chuck assembly to a point just past the next station and repeats the operation. Between paint applying operations the chuck is constantly rotating at a speed greater 70 than when rotated by the paint applying discs 75

to evenly distribute the paint and prevent it from running and to whip the tail of the paint into alignment. After both series of bands have been applied the operator swings the next chuck into operating position, applies a new tumbler and repeats the above described steps. Thus the first mentioned tumbler is gradually moved about the machine and is constantly rotating. The drier manifold 104 directs heated air upwards against the rotating tumbler for about 160° of its travel 10 after leaving the second paint applying station. When the tumbler reaches a position at the end of the drier and at the start of rail 106, the valve follower 73 is moved upwardly by cam 29, thus cutting off the vacuum supply to the chuck and 15 opening the exhaust port 62 to admit air under atmospheric pressure to the tumbler. The spring 47 on the chuck then forces the head 45 back against the stop 46 and releases the banded tumbler which is protected from falling from the 20 chuck by the rail 106. The tumbler rides thusly until removed by an operator.

It is obvious that more paint applying stations may be added if desired and that the reservoirs shown may be divided to hold different colored 25 paints.

I claim:

1. A banding machine for decorating articles comprising a base, a turret rotatably mounted on said base, a plurality of horizontally extending, 30 vertically pivotable, rotatable chucks mounted at spaced intervals on said turret and adapted to move about a common center, a plurality of paint applying stations positioned arcuately about the turret, each comprising a rotatable 35 shaft aligned radially of the turret and a plurality of rigid, spaced paint applying discs mounted resiliently thereon so as to be yieldable vertically, and paint reservoirs to supply paint to said discs, means for moving the chucks from 40 station to station, means carried by the turret for causing the rotation of the chucks, means for positioning the chucks at the stations and holding them against lateral movement while paint is being applied to the articles on the 45 chucks, and means for moving the chucks vertically to contact the discs.

2. A machine for applying colored bands to articles comprising a base, a turret rotatably mounted on said base, a plurality of supports 50 extending from said turret and vertically pivotable thereon, paint applying discs positioned about the turret, paint reservoirs for supplying paint to the discs, means for positioning the supports at the discs and means for moving the supports vertically to the discs.

3. A machine for applying colored bands to articles comprising a base, a turret rotatably mounted on said base, a plurality of chucks extending from said turret, paint applying discs 60 positioned about said turret, paint reservoirs for supplying paint to the discs, means for holding the articles to be banded on the chucks, means for releasing the articles from the chucks when finished and an arcuate guard rail adjacent the 65 path of the ends of the chucks for a predetermined distance from the point where the articles are released.

4. A machine for applying colored bands to articles comprising a base, a turret rotatably 70 mounted on said base, a plurality of chucks extending from said turret, paint applying discs positioned about said turret, paint reservoirs for supplying paint to the discs, means for causing vacuum at each chuck to hold the article to be 75

banded thereon, means for releasing the vacuum to release the article from the chuck, and a horizontally adjustable arcuate guard rail adjacent the ends of the chucks for a predetermined distance from the point where the article is released from the chuck.

5. A machine for applying colored bands to articles comprising a base, a turret rotatably mounted on said base, a plurality of supports extending from said turret, paint applying discs positioned about the turret, paint reservoirs for supplying paint to the discs, a stationary plate positioned below the turret, a vertically yieldable follower for each support depending from said turret, and stop grooves in the paths of said followers for accurately positioning the respective supports over the paint applying discs.

6. A machine for applying colored bands to articles comprising a base, a turret rotatably mounted on said base, a plurality of chucks extending from said turret, paint applying discs positioned about the turret, paint reservoirs for supplying paint to the discs, a vacuum system leading to each chuck for holding the articles to be banded on the chuck and automatic means for releasing the vacuum from each chuck to release the article therefrom at a predetermined position of the chuck.

7. A machine for applying colored bands to articles comprising a base, a turret rotatably mounted on said base, a plurality of chucks extending from said turret and vertically pivotable thereon, rotatably mounted paint applying discs arranged circumferentially of the turret, means for positioning the chucks over the discs, means for continuously rotating the discs and a clutch connection permitting the chucks to be rotated by the discs when the article to be banded is in contact therewith and operably joining them for rotation with other means at all other times.

40 8. A machine for applying colored bands to articles comprising a base, a turret rotatably mounted on said base, a plurality of chucks extending from said turret and vertically pivotable thereon, rotatably mounted paint applying discs arranged circumferentially of the turret, means for positioning the chucks over the discs, means for continuously rotating the discs, a continuously rotating friction plate adjacent the inner ends of the chucks, drive wheels on the inner ends 50 of the chucks, spring means normally holding the drive wheels in contact with the friction plate whereby the chucks are rotated, said drive wheels being positioned to be moved out of contact with said plate when the chucks are pivoted downwardly to cause the article to be banded to contact the paint applying discs.

9. A machine for applying colored bands to articles comprising a base, a turret rotatably mounted on said base, a plurality of chucks extending from said turret and vertically pivotable thereon, a vacuum system leading to each chuck, a valve for each chuck carried by said turret, a port at the end of each chuck normally closed but adapted to be opened automatically when an article is positioned thereon to hold the article on the chuck, a stationary plate below the turret, a cam on the plate, a follower on each valve above the cam adapted to be moved by the cam at a predetermined position of the chuck to close the source of vacuum and admit air at atmospheric pressure to the chuck whereby the article on the chuck is released.

10. A machine for applying colored bands to articles comprising a base, a turret rotatably

5 mounted thereon, a plurality of chucks extending horizontally therefrom and pivotably mounted thereon, rotatably mounted paint applying discs positioned beneath the path of the chucks, paint reservoirs for said discs, a vacuum system leading to each chuck for holding the article to be banded on the chuck, a valve for controlling the vacuum to each chuck, means for positioning the chucks over the discs, drying means positioned under the path of the chucks 10 for a predetermined distance from the paint applying discs that apply the last series of bands for directing heated air upon the article, an arcuate guard rail positioned adjacent the path of the ends of the chucks for a predetermined 15 distance from the end of the drier means, and automatic means for exhausting the vacuum from each chuck when the chuck reaches the start of the guard rail whereby the article is released from the chuck and protected by the 20 rail.

11. A banding machine comprising a rotatable turret, a plurality of rotatable chucks extending therefrom and pivotably mounted thereon, paint applying discs positioned adjacent the path of the chucks, a vacuum system leading to each chuck for holding articles thereon while being treated, a valve for each chuck mounted on the turret for controlling the vacuum, means normally holding said valves open so that vacuum 30 is present at the chucks, a valve follower depending from each of said valves, a vertically yieldable positioner depending from said turret for each chuck, a stationary plate positioned below the turret, a cam on said plate adapted to 35 move said valve followers to release the vacuum from the chucks at predetermined positions and grooves in said plate for said positioners whereby the chucks may be accurately positioned over the discs.

40 12. A machine for applying colored bands to articles comprising a base, a rotatable turret mounted on said base, chucks extending horizontally from said turret, paint applying stations positioned about the turret and each comprising 45 rotatably mounted paint applying discs arranged axially of the turret, said chucks adapted to be rotated by the discs when paint is being applied to the articles carried thereon and independent means for rotating the chucks between paint 50 applying operations.

13. A machine for applying colored bands to articles comprising a base, a turret rotatably mounted on said base, a plurality of chucks extending from said turret, a series of paint applying discs positioned about said turret and adapted to successively contact the sides of the articles carried by the chucks to apply paint thereto, paint reservoirs for supplying paint to the discs, means for holding the articles on the chucks, an arcuate manifold positioned adjacent the path of the chucks for a predetermined distance from the last series of discs, means for blowing air through said manifold and onto the glass articles to dry the paint thereon, means 60 for rotating the chucks as they pass by the manifold, means for automatically releasing the articles from the chucks after passing the manifold and an arcuate guard rail adjacent the ends of the chucks extending from the end of the 65 manifold for a predetermined distance.

14. A machine for applying colored bands to articles comprising a plurality of movable chucks, paint applying discs positioned adjacent the path of the chucks, reservoirs for supplying paint to 75

- the discs, means for moving the chucks to the discs, means for causing vacuum at each chuck to hold the article to be banded thereon and means for releasing the vacuum from the chuck 5 at a predetermined position to release the article when the banding is finished.
15. A machine for applying colored bands to articles comprising a plurality of movable chucks, a plurality of series of paint applying discs positioned adjacent the path of the chucks, means for moving the chucks from one series of discs to another, means for causing vacuum at each chuck to hold the article to be banded thereon, a manifold for directing air upon the article after 10 the bands have been applied to dry the paint, automatic means for causing the chuck to rotate during the drying and automatic means for releasing the vacuum to release the article after the drying operation.
- 20 16. A machine for applying colored bands to articles comprising a plurality of movable arms, supports rotatably mounted on said arms, a plurality of series of paint applying discs adjacent the path of the supports, means for moving the supports from one series of discs to the next for transferring the paint from the discs to the articles on the supports, a yieldable follower secured to each arm, and stop shoulders in the path of the followers for accurately positioning 25 the supports relative to the discs for the paint applying operation.
17. A machine for applying colored bands to articles comprising a chuck, paint applying discs adapted to rotate the chuck when applying paint 30 to the article carried by the chuck and independent mechanical means for rotating the chuck immediately after rotation by the discs.
18. A machine for applying colored bands to articles comprising a chuck, paint applying discs adapted to rotate the chuck when applying paint to the article carried by the chuck and independent mechanical means for rotating the chuck at greater speed immediately after rotation by the discs.
19. A machine for applying colored bands to articles comprising a base, a rotatable turret mounted on said base, chucks extending horizontally from said turret, paint applying stations positioned about the turret and each comprising rotatably mounted paint applying discs arranged axially of the turret, said chucks adapted to be rotated by the discs when paint is being applied to the articles carried thereon and independent means for rotating the chucks at increased speed 35 between paint applying operations.
20. A method of forming a band on an article comprising rotating the article while in contact with a paint applying member and rotating the article at increased speed when such contact ceases to whip the tail of the paint into alignment with the applied band and to evenly distribute the banding material to produce a band of substantially uniform thickness.
21. A method of forming a band on an article 40 having an impervious surface comprising rotating said article while in contact with a paint applying member, breaking contact between said article and member and rotating the article at increased speed simultaneously with breaking of its contact with said paint applying member to whip the tail of the coloring matter forming the band into alignment with the applied band to thereby evenly distribute the banding material uniformly throughout the band.
22. The method of coating predetermined por-

tions of an article having an impervious surface comprising rotating said article while in rolling contact with a coating material, breaking contact between said article and coating material and rotating said article at increased speed simultaneously with the breaking of said contact to whip the tail of the coating material into alignment with the applied coating to thereby evenly distribute the coating material.

23. A machine for applying colored bands to articles, comprising a chuck, paint applying discs adapted to rotate the chuck when applying paint to the article carried by the chuck, and independent means for automatically rotating the chuck immediately after rotation by the discs, the latter 15 comprising a rotating friction plate and a clutch connection between said chuck and said plate.

24. A machine for applying colored bands to articles comprising a chuck, paint applying discs adapted to rotate the chuck when applying paint 20 to the article carried by the chuck and independent means for automatically rotating the chuck at greater speed immediately after rotation by the discs, said independent means comprising a rotating friction plate and a clutch connection 25 between said chuck and said friction plate.

25. A machine for applying bands to impervious articles comprising a base, a turret rotatably mounted upon said base, a plurality of article holding chucks on said turret, articles thereon, 30 a vacuum system leading to each chuck for holding said articles in a position to be banded, a reservoir for banding material, a banding disc positioned for successive article contact and having peripheral portions disposed in the banding 35 material, means individual to the disc permitting resilient article contact, means for effecting relative rotation between the disc and article to apply a banding and means for releasing the vacuum from the chucks in succession to release the 40 articles after banding.

26. A machine for applying bands to impervious articles comprising a base, a turret rotatably mounted upon said base, a plurality of article holding chucks on said turret, articles thereon, 45 a vacuum system leading to each chuck for holding said articles in position to be banded, a reservoir for banding material, a plurality of banding discs positioned for successive peripheral article contact and having portions of their periphery disposed in the banding material, means individual to each disc permitting resilient article contact, means causing relative rotation between the discs and article to apply a series of bands and means for releasing the vacuum from the 50 chucks in succession to release the articles after banding.

27. A machine of the character described comprising a carrier, chuck mechanism mounted upon the carrier and including a housing pivoted for 60 vertical swinging movement relative to the carrier, an article support rotatably mounted in said housing and including a shaft and a drive wheel at the inner end of said shaft, means for actuating said carrier and thereby moving the chuck 65 mechanism past loading and banding stations, rotating banding disks at the latter station, means whereby the chuck mechanism may be swung vertically between two operating positions in one of which the article contacts and is rotated by 70 said disks, and driving means for imparting motion to the drive wheel when the chuck mechanism is in another of its positions.
